to Donald Gottwald, Akron, Ohio

Application October 4, 1938, Serial No. 233,223

7 Claims. (Cl. 123—79)

This invention relates to valve mechanism for use in internal combustion engines and is more particularly directed to mechanism of the type employing a single valve through which the intake gas is passed to the cylinder and the exhaust gas removed therefrom.

Mechanisms of this general type are very old and it has frequently been proposed to provide a single poppet valve providing access to the cylinder for both the exhaust and intake gases and combined with a second valve to alternately effect a fuel intake or fuel discharge as desired. These prior mechanisms have been subjected to the disadvantage that both the intake and exhaust lines were open at the same time for an appreciable and uncontrolled period during operation. This time period was sufficient to blow exhaust gas back into the intake line and nullify the otherwise efficient characteristics of the design. In some cases the hot exhaust gas would ignite the intake gas and pre-explode the fuel before it had passed beyond the second valve. With mechanisms of this type it has heretofore not been possible to control the degree of overlap between the period the exhaust valve is open and the period the intake valve is open. Expressed in another way, the inertia and speed limitations in valve mechanisms, from a practical standpoint, prevent the instantaneous opening of a valve. Therefore the valve must open as a result of appreciable movement.

I have found that if I provide a sleeve valve which may simultaneously commence to move to seal one port and at the same time continue to seal the other port until such time as the operating characteristics of the engine demand that the latter port be opened I can effectually employ a single poppet valve to function as both intake and exhaust to the cylinder. In certain cases it is desirable to maintain one port entirely closed during the period the other port is open and in other engines with other operating characteristics, what I term a controlled degree of overlap of valve opening should be employed to allow both ports to be open during a short period of the engine cycle. This period should not exceed 60 degrees of crankshaft rotation or 30 degrees of camshaft rotation, the latter shaft rotating at one-half the crankshaft speed.

The cardinal object of this invention has been to provide a valve mechanism for internal combustion engines which will permit of a large area of cylinder valve with respect to a given cylinder diameter than has heretofore been possible and

thus to improve the volumetric efficiency of the engine.

An additional object of my invention has been to overcome the operating disadvantages with former related constructions by providing a valve mechanism with a controlled degree of overlap for the most efficient operation of the engine by which there is no possibility of both the intake and exhaust lines being open to the cylinder beyond a desired time. As a related object of my invention I am enabled by the valve mechanism itself to time the intervening period between closing the exhaust line and opening the intake line.

To the accomplishment of the foregoing and related ends, said invention, then, consists of the means hereinafter fully described and particularly pointed out in the claims; the annexed drawings and the following description setting forth in detail certain structure embodying the invention, such disclosed means constituting, however, but one of various mechanical means in which the principle of the invention may be used.

In said annexed drawings:

Figs. 1, 2, 3 and 4 are similar sections through my improved valve mechanism showing respectively the position of the parts during the power, exhaust, intake and compression strokes; and

Fig. 5 is a section through Fig. 2, as indicated by the lines 5—5 thereon.

Referring now to the drawings, I provide a cylinder block 10 in which is formed one or more cylinders 11, accommodating a piston 12, to which is connected the usual connecting rod 14 for engagement with the crankshaft. A head 15 is bolted to the block 10 and supports the valve mechanism hereinafter described.

The head 15 is formed with an intake conduit 17 and an exhaust conduit 18 opening into a valve casing 20, which communicates with an explosion chamber 22 in communication with the main cylinder 11.

A poppet valve 25 seats against the cylinder head at 26 and is provided with a stem 28 slidably received in a core 30. The core which functions as a valve stem guide, includes a head portion 31 by which the same is secured to the head within the valve casing 20 and in position to effectively seal the same at its upper end. An annular boss 33, formed as indicated in the drawings, on the lower portion of the core coacts with the valve casing wall to form a sliding valve seat as hereafter described.

To seal the intake conduit 17 from the exhaust conduit 18, a sleeve valve 35 is provided recip-

roable between the boss 33 and the adjacent casing side wall. As best shown in Figs. 2 and 3, the sleeve cross-section is of such length and configuration that during its downward movement 5 to seal the exhaust conduit it will maintain the passage from the intake conduit closed for the desired period of time. The depth of the valve sleeve by which this is accomplished may be varied in length to provide some latitude between 10 the final sealing of the exhaust conduit and the instant at which the intake is opened. This feature, which I call the controlled degree of overlap, allows the original design of the mechanism for a given result independent of adjustment of 15 the camshafts.

During the exhaust stroke, as shown in Fig. 2, the sleeve is in its upper position and the exhaust gases pass around the open poppet valve and out through the exhaust conduit 18. At the 20 conclusion of the exhaust stroke the sleeve 35 is lowered and seals off the exhaust. The sleeve proceeds on downwardly, as shown in Fig. 3, to open a port between its upper portion and the annular boss 33. Thus intake gas may be sucked 25 past the sleeve and past the poppet valve into the explosion chamber of the cylinder. At the termination of this operation the poppet valve closes and the piston 12 rises to effect the compression stroke, which is immediately followed by ignition 30 and the power stroke in a manner well known in the art and not further described.

To actuate the sleeve 35 the mechanism shown in Fig. 5 is provided. This consists of a pair of upwardly extending ears 38 on opposite sides of 35 the sleeve and extending above the spring cover 40, which surrounds the valve casing 20. Each ear is provided with a horizontal lug 42 to position the compression spring 45 between it and a shoulder on top of the cylinder head. The normal tendency of the springs 45 to retain the sleeve 40 in the upper position shown in Fig. 1 is counteracted by cams 47 on a camshaft 50 which is driven, as well understood, in timed synchronism with the crankshaft. To actuate the poppet valve, a cam 52 is provided, adapted to ride over a cap 45 53 bearing on top of the valve stem and guided in a guideway 54 of the valve cap 40. A spring ring 55 is secured to the upper end of the valve stem and a compression spring 57 is interposed between the ring and the portion 31 of the core 30.

From the present mechanism just described, it will be apparent that the sleeve and poppet valve are normally retained in the upper positions shown in Fig. 1, due to the action of their respective springs and that the downward motion 55 of each valve member is effected by the corresponding cams on the cam-shaft 50.

From the foregoing description it will be apparent that I have provided an improved valve mechanism by which a single valve opens into 60 the power cylinder and when open serves as a passage for both intake and exhaust gases and improves the volumetric efficiency of the engine. The continually cooling effect of intermittent charges of intake gas largely nullifies the harmful effects of the hot exhaust gas and also prevents the precipitation of carbon at the valve seat. The controlled degree of overlap in the sleeve 35 permits entirely sealing either the intake 65 or exhaust conduit to the poppet valve before the other passage is opened.

Other modes of applying the principle of my invention may be employed instead of the one explained, change being made as regards the 70 structure herein disclosed, provided the means

stated by any of the following claims or the equivalent of such stated means be employed.

I therefore particularly point out and distinctly claim as my invention:

1. In an explosion engine, a cylinder structure, 5 a piston in said cylinder, a valve casing in communication with said cylinder and concentric therewith, a valve seat in said piston cylinder, a core in said valve casing with a valve stem guide coincident with the valve axis, a valve with 10 a stem slideable in said guide to coact with said seat and seal the cylinders and casing from each other, resilient means to normally seat said valve, an intake and an exhaust conduit each opening to said valve casing, a sleeve slideable in said valve 15 casing between the core and side wall portion to control passage of gas between the intake conduit and the valve casing and between said exhaust conduit and said valve casing, said sleeve acting to completely seal one conduit from said valve 20 casing before opening the other conduit to said valve casing, and means to actuate said valve and said sleeve.

2. In a valve mechanism for an internal combustion engine, a cylinder, a poppet valve and a 25 seat therefor in communication with said cylinder and a casing, a sleeve valve mounted to reciprocate coaxially with the poppet valve in said casing, a core in said casing an exhaust conduit and an intake conduit in communication with 30 said casing, one of said conduits opening past said sleeve valve axially of said cylinder, and the other opening transversely thereof in a region closely adjacent said first opening, said sleeve valve coacting with said core to control said axial 35 opening with the inner axial face thereof and to control said transverse opening with the outer axial face thereof, means to reciprocate said sleeve valve to alternately open said intake and said exhaust to effect a passage of intake and 40 exhaust gas past said poppet valve and seat, said sleeve formed to seal said intake conduit in a region closely adjacent said exhaust conduit to prevent the accumulation of an appreciable volume of exhaust gas in said casing after said exhaust conduit is closed.

3. In an explosion engine, a cylinder block having a cylinder, a valve casing in communication therewith, said casing having two ports opening therein, a stationary core in said casing, a sleeve valve in said casing, said sleeve valve being adapted for coaction with said core for sealing one of 50 said ports and having a surface adapted to cover the other of said ports.

4. In an overhead valve internal combustion 55 engine, the combination of a valve casing having two ports and an aperture opening therein, a core projecting into said casing, a valve member slideable within the core for closing said aperture, a sleeve having an outer axial surface adapted for covering one of said ports and an inner axial surface adapted for coaction with said core for controlling the other of said ports.

5. In a valve mechanism, the combination of a 65 valve casing having an opening for communication with a power cylinder, a conduit opening into said casing, a core projecting into said casing, a valve member slideable within the core for closing said opening, a sleeve in sliding engagement with said casing and said core, means for intermittently breaking the engagement between said sleeve and said core whereby said conduit and said opening communicate through the opening 70 of said sleeve.

6. In a valve mechanism, a valve casing having 75 therein two openings, a sleeve slideable in said

casing between said openings, a poppet valve member associated with the sleeve, means for sealing communication between the valve member and the sleeve and means for actuating said sleeve whereby said openings are intermittently in communication with each other.

5. 7. In an explosion engine, a cylinder structure, a cylindrical valve casing, a valve seat in communication with said cylinder and said casing, 10 a core in said casing having a valve stem guide

therein, a valve with a stem slideable in said guide for coaction with said valve seat for sealing said valve casing from said cylinder, an intake conduit and an exhaust conduit each opening in said valve casing, a sleeve valve for covering one of said conduits, the other of said conduits being controlled by coaction between said casing, sleeve valve and core, and means for actuating said valves.

HARRY L. HOSTERMAN. 10
